(57) **CLAIM**

The ornamental design for a pill crusher, as shown and described.

DESCRIPTION

FIG. 1 is a perspective view of a first embodiment of a pill crusher according to our design;

FIG. 2 is a front view thereof, the rear view being a mirror-image thereof;

FIG. 3 is a right side view thereof, the left side view being a mirror-image thereof;

FIG. 4 is a top view thereof; and,

FIG. 5 is a bottom view thereof, the portions shown in broken lines forming no part of the claimed design.
